By Daniel Breed

UNITED STATES PATENT OFFICE.

JACOB H. SHELLABARGER, OF TOPEKA, KANSAS.

STOCK-CAR.

SPECIFICATION forming part of Letters Patent No. 256,389, dated April 11, 1882.

Application filed December 23, 1881. (No model.)

To all whom it may concern:

Be it known that I, JACOB H. SHELLABARGER, a citizen of the United States, residing at Topeka, in the county of Shawnee and State 5 of Kansas, have invented certain new and useful Improvements in Stock-Cars or Cattle-Cars; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 The object of my invention is to construct a car for the transportation of live stock that shall be comfortable, convenient, and readily adapted to the varied needs of that class of freight, and at the same time be readily convertible into an ordinary freight or merchandise car, enabling the railroads to use it for return 20 freight, if desirable, instead of hauling it back empty, as heretofore.

In the accompanying drawings, in which 25 similar letters indicate corresponding parts throughout, Figure 1 is a plan view of my improved stock-car. Figs. 2 and 3 are detail views of the stall-partitions. Figs. 4 and 5 are detail views of the end and center troughs. 30 Fig. 6 shows the center cross-piece and the cleats thereon. Fig. 7 is a view of inside of car, showing arrangement of stall and troughs. Fig. 8 shows the usual door-bar adapted to receive a bar placed between the stalls to keep 35 the stock apart. Fig. 9 is a side elevation of car with one door open, allowing partial view of its interior.

The car A is constructed with four doors, two on each side opposite each other. Said doors 40 S are hung on rollers in the ordinary manner. Within the car, at about its center, is placed cross-piece b, having cleats l on each side, and similar cleats l are fixed at each end of the car. The partitions F, constructed of wood or similar 45 material, bounded on their edges with iron to prevent the stock injuring them, are provided with pins d e and formed with the angular notch h k and oblique corners g. When in use the ends C of partitions F are placed between 50 cleats l and the pins d e into corresponding sockets fixed in the floor, and thus

the partition is secured in position. Partitions F are formed with notches h k, in which, when in position, the troughs b' and b'' rest. The parts F are all of same size, and are thus completely 55 interchangeable. The troughs b' fit notches h k. The trough b'' is twice as large and made to fill up the double-sized space across the center of car formed by the notches of the double set of partitions meeting on that line. Hooks 60 m are provided for hanging the troughs to the ceiling when out of use.

The operation of fitting up my stock-car is as follows: Stationary cleats a' are fixed inside the car at each end and center, the center 65 cross-piece, b, is placed in position, and the partitions are set up lengthwise of the car and secured by cleats and pins d e. Troughs b' and b'' are laid in place across the ends and center partition, and the car is ready for use. When 70 loaded the cross-bar p is secured to door-bar r by screws n, and serves to prevent the cattle from touching each other.

By means of the arrangement shown and described I can have four or five stalls across 75 an ordinary car, according to size of cattle, and am enabled to load my cars from either or both sides. The cattle are always standing lengthwise of the car, in which position they are better able to brace themselves against the strain 80 on them during variations of speed and jerking of the car in starting and stopping, to which they would be subject if placed crosswise. They are readily accessible to attendants, and by use of the troughs and open-work of the car 85 are easily and conveniently watered and fed.

The advantages of my construction are, among others, that the cattle stand lengthwise or in the direction of motion, complete adaptability to different-sized cattle or horses, conveniences 90 for feeding and watering, the accessibility to attention, and convenience of loading into both compartments at once made practicable by my arrangements of parts. When the trip is ended and the car no longer needed for cattle 95 the partitions, cross-bars, and troughs are simply lifted out of place and stored at one end of the car or in a suitable bin constructed under the center of the car. The car can then be used for coarse freight, and by reason of its double 100 set of doors is particularly suited to the carriage of lumber and other lengthy articles.

Having thus described my invention, what I claim, and desire to secure by Letters Patent, is—

1. In combination with car A, having double set of doors S, arranged opposite each other, the adjustable longitudinally-arranged stall-partitions F, and troughs b' b'', secured at each end and center of the car, thereby forming aisles across the car from door to door, through which the cattle enter the stalls, as shown and described.
2. The stalls or removable partitions F, bound on their edges with metal, and formed with

notches h k and provided with pins d e, in combination with cross-piece b, stationary cleats a', and cleats e, as and for the purpose specified.

3. In combination with car A, having double set of doors S and provided with stationary cleats a', the cross-piece r, removable and interchangeable stall-partitions F, troughs b' b'', and cross-bar p, all arranged for operation substantially as shown and described.

JACOB H. SHELLABARGER.
